Inventor:

Olois Reichling

UNITED STATES PATENT OFFICE.

ALOIS REICHLING, OF KAADEN-ON-THE-EGER, CZECHOSLOVAKIA.

HAND HAMMER.

Application filed June 11, 1925. Serial No. 36,536.

To all whom it may concern:

Be it known that I, ALOIS REICHLING, a citizen of the Czechoslovak Republic, and residing at Kaaden-on-the-Eger, Bohemia, Czechoslovakia, have invented certain new and useful Improvements in a Hand Hammer, of which the following is a specification.

This invention relates to an improved hand hammer, of the kind having detachable means for fastening the hammer head to its shaft and essentially consisting of a central fastening rod passed through said shaft, and its novelty consists in making the hammer head of an upper and a lower member fitting one another and having at one end a hingelike transverse bulb-and-groove engagement, this permitting to use the hammer head for holding or clamping any implement therein such as for instance a screw-driver, chisel, or the like.

The accompanying drawing illustrates the improved hammer: Fig. 1 is a sectional side view, Fig. 2 an end view, and Fig. 3 a plan view of the same, while Fig. 4 is a similar view to that shown in Fig. 1, representing how the hammer can be used for clamping a screw-driver therein, and Fig. 5 shows a detail in cross-section.

According to the invention, the hammer head consists of an upper and a lower member *a*, *b* fitting one another and having at one end a transverse bulb-and-groove engagement at *c* forming a kind of hinge thereon; the hammer head having as usual an opening therein for the reception of its shaft.

As known in the art, the hammer shaft *d* is tapered and has a central boring therein, in which a round-iron rod *e* is slidably inserted. Said rod projects with its lower end *f* beyond the central boring in the shaft *d* and is there screw-threaded for the reception of a fly-nut *g* which partly engages in a recess *h* in the shaft *d* having a soft-leather washer *i* therein. The upper end of the rod *e* carries a fixed square top plate *k* engaging in a corresponding recess *l* in the upper hammer head member *a* so as to be

flush therewith, the part *m* of the rod directly beneath said plate being of star-shaped cross-section (Fig. 5) and engaging in the upper end of the central boring in the shaft *d*.

For fastening the tapered shaft *d* to the hammer head *a*, *b*, the same is passed with its upper end from below in the opening in the hammer head and the rod *e* is inserted from above in the central boring in the shaft until its top plate *k* is flush with the top of the hammer head and its lower end *f* projects beyond the shaft *d*, whereupon the fly-nut *g* is screwed thereon and tightened, which acts to pull the star-shaped part *m* of the rod in firm engagement with the upper end of the central boring in the shaft *d* so that the latter is prevented from turning. Owing to the soft-leather washer *i* forming an elastic cushion for the fly-nut *g*, the latter is prevented from unintentionally getting loose.

By the hammer head being formed of two members, it is possible, after somewhat loosening the fly-nut *g* and opening the hammer head at one end while its two members *a*, *b* turn then about the hinge *c*, to insert any implement such as a screw-driver *n* (Fig. 4) between said two members and to clamp the same therein, for its intended use, by again tightening the fly-nut *g*. In the same way, the hammer head can be used for straightening bent nails or the like.

What I claim is:—

A hand hammer comprising a hammer head and a shaft, and detachable means for fastening said head to said shaft, said hammer head consisting of an upper and a lower member fitting one another and held together by said fastening means, and a hingelike transverse bulb-and-groove engagement between said upper and lower member at one end of said hammer head, substantially as and for the purpose set forth.

In testimony whereof I have hereunto set my hand.

ALOIS REICHLING.
